UNITED STATES PATENT OFFICE.

MORRIS U. BERNHEIM, OF OAKLEY, OHIO, ASSIGNOR TO THE ALVEY-FERGUSON COMPANY, OF OAKLEY, CINCINNATI, OHIO, A CORPORATION OF OHIO.

CONVEYING MECHANISM.

1,278,577.

Specification of Letters Patent. Patented Sept. 10, 1918.

Application filed July 9, 1915. Serial No. 38,866.

To all whom it may concern:

Be it known that I, MORRIS U. BERNHEIM, a citizen of the United States, residing at Oakley, in the county of Hamilton and State 5 of Ohio, have invented certain new and useful Improvements in Conveying Mechanisms, of which the following is a specification.

This invention relates to conveying apparatus and one of its important purposes 10 is to provide an improved conveying structure arranged to safely and rapidly transfer filled bags or other packages along a level of readily variable length and in readily variable directions and from said level 15 to a different one, and to deposit said packages safely and in piles at any desired point of storage.

The conveying apparatus forming the subject matter of the present invention is also 20 adapted to transfer packages from wagons or cars and pile the same in any part of the room of a warehouse or other place of storage or from said storage place to wagons or 25 cars or from one part of a room to another part of the same room or from one room to another room on a different level.

In pursuance of the main or ultimate purpose of the invention I have provided a 30 structure which is characterized, among other things which will appear from the following description, by the facts:

First: that it comprises a series of readily separable and unitable movable sections, 35 each having a frame, an endless traveling apron, a shaft which extends lengthwise of the frame, driving connections between the shaft and the apron adapted to impart positive movement to the latter in the direction of the length of the shaft, and universal 40 connections between the confronting ends of shafts of the several sections, whereby one of said shafts will be driven by another and each will impart the described traveling movement to the apron of its section regardless of the angle which said shaft and 45 apron of one section occupies with reference to the similar part of the next section;

Second: that it comprises an elevator 50 which is readily removable from place to place, has an endless traveling apron which moves in planes whereby it is adapted safely

and without jar to the packages or its mechanism to receive packages from or deliver the same to the foregoing sections, and has a 55 discharging slide, the delivery end of which is adjustable laterally as well as vertically for delivering bags from the elevator to a predetermined place within the range of its 60 adjustments, to a storage pile being built up by the system.

Third: that the discharging end of the elevator is mounted to swing horizontally upon an arc of a circle while its receiving end remains in co-operative relation to the 65 sections which convey the packages along the level by virtue of which construction the discharging end of the elevator may be swung at will to that position which will best serve to deposit the packages in piles 70 and in tiers.

The parts are also characterized by features entering into the details thereof, whereby important advantages in respect of 75 strength, effective utilization of power, portability, and ease of disconnections of sections and their assemblage into a system of a required length, extending in required directions to and from any required place, are secured, all as will hereinafter fully appear.

The several objects of the invention are well accomplished by the construction illustrated in the accompanying drawings serving to exemplify the invention. In the 85 drawings:

Figure 1 is a perspective view of a conveying apparatus constructed in accordance with the invention.

Fig. 2 is a perspective view of one of the 90 conveyer sections and a part of another of said conveyer sections illustrating the driving connection between them.

Fig. 3 is a detail perspective view of a 95 slide leading from the delivery end of the elevator.

Fig. 4 is a rear end view of said slide and the portion of the elevator to which it is secured.

Fig. 5 is a detail view partly in section, 100 illustrating the wheeled and swiveled mounting for the delivery end of the elevator.

Fig. 6 is a side elevation of the lower end of the elevator.

Fig. 7 is a cross section thereof on line 7—7 of Fig. 6.

Fig. 8 is a like view upon line 8—8 of Fig. 6;

Fig. 9 is a cross section through one of the conveyer sections upon line 9—9 of Fig. 2; and

Fig. 10 is a detail view of one end of one of the conveyer sections illustrating a take-up hereinafter described.

Like reference characters designate corresponding parts throughout the several views of the drawings.

A complete system made in accordance with the present invention is composed of any desired number of portable apron-conveyer sections A—A' and an elevator B also here shown as of the apron type. These elements are of such a nature that when brought into coöperative relation they are adapted to provide an apparatus capable of ready variation in length and in the angles which the several elements may occupy with respect to each other.

The section A comprises a portable frame of suitable length and of a construction, hereinafter set forth, whereby it is strong and light and furnishes guidance for an endless traveling apron of suitable character, here shown as being composed of a pair of endless traveling chains 1, connected with each other by a series of slats 2 which extend transversely of the frame and have their ends secured to the links of the chains.

These slats serve as the support for the filled bags or other packages being conveyed. In order to cause this apron to move longitudinally of the frame, a driving mechanism of a particular character is employed.

This driving mechanism essentially includes a shaft 5 which extends longitudinally of the frame and has a driving connection with one end of the apron whereby upon its rotation it will impart traveling movement to the latter in the direction of the length of the shaft.

At the other end of the shaft 5 there is an element 8 of a universal connection, the mate 8^a of which is carried by the contiguous end of the similar shaft

5^a of the next section A'. This driving connection, for the type of apron conveyer herein illustrated, includes sprockets 3 which are engaged by the chains 1 and are mounted on shafts 4 at the opposite ends of

the frame, and toothed gearing connecting the shaft 4 at the driving end of the frame with the shaft 5. A most desirable form of gearing consists of a bevel gear 6 fixed on the shaft 5 and a similar gear 7 fixed on the contiguous shaft 4 and intermeshed with the gear 6.

The frame of the section A is composed of longitudinal side bars 10 formed of angle irons constituting tracks for the chains 1, which chains are preferably provided

with rollers 1^x which run on said tracks and minimize friction. These longitudinal members at each side of the frame are connected with each other by vertical straps or members 11 and also by diagonal members 12; and the two side frames thus formed are connected with each other by transverse members 13 which are arranged at intervals and are riveted or otherwise strongly secured to the vertical members 11 at places between the working and returning runs of the apron, as shown in Fig. 9, whereby the frame is strongly braced. The frame is also mounted upon wheeled supports, located under the ends thereof and secured thereto. These supports are here shown comprising vertical members 14 and transverse members 15, each composed of angle irons, strongly secured together and provided with supporting wheels 16. This wheeled support is of such construction as to adapt it to also support a suitable prime mover C and for this purpose comprises uprights 17 and suitable means supported thereby for the motor and the driving connections. The motor here shown is electric and drives by means of suitable gearing, only part of which is shown, to a shaft 20. This shaft 20 carries a sprocket wheel 21 which drives a chain 22 serving to communicate movement to a second sprocket wheel 23 fixed on the shaft 5.

The section A' may be, and is here shown as being, identical in construction with that of the section A, except for such changes as are necessary to adapt it to be driven by the shaft 5 of the latter, instead of by a prime mover. Hence, there is no provision in it for the prime mover C, and its longitudinal shaft (5^a) instead of having a universal-joint member 8^a at one end only, has such a member at both ends, whereby it is adapted for connection with the shaft 5 at one end and also with a similar shaft at its other end, forming part of the next section. It will be apparent that rotative movement imparted to the shaft 5^a from the shaft 5 will operate, through the gears 6^a and 7^a and sprocket wheels 3^a and the shafts of the latter, to transmit traveling movement to the apron of the section A' in the direction of the length of the frame of the latter, precisely the same as the shaft 5 causes traveling movement to be imparted to the apron of the section A.

It will be observed that the described universal connection enables the sections A and A' to be arranged at any desired angle with reference to each other without interfering with the transmission of movement to the apron of one section from the shaft of the preceding section.

In order also that the sections may be readily disconnected and reunited, the complementary members or mates 8 and 8^a of

the universal connection are connected with each other by readily removable connections, as pins 9 removably extending through the spiders 9^a in the type of universal connection herein shown.

5 In practice, the system will include a section A and several sections A', placed together end to end, in direct line with each other or at an angle or angles, to accord with required conditions, and where the conditions are variable, sections may be removed from or added to the line, and moved readily from place to place, all as herein set forth.

10 15 It will be noted that the longitudinal shaft 5 has a driving connection to the transverse shaft 4—carrying the sprockets 3—at one end only of the section A, the transverse shaft carrying the sprockets at the other end 20 of the section being free from connection to the longitudinal shaft 5. This is true also with respect to corresponding elements 25 of the section A'—the longitudinal shaft 5^a of the latter being connected by gears (6^a and 7^a) to the transverse shaft carrying the sprockets 3^a at one end only of the section A'. Accordingly, adjustment of the transverse shafts and sprockets, at the ends of the sections A and A' which are not connected to the shafts 5 and 5^a, to regulate 30 length of the aprons or take up slack therein, may be effected without disturbing the connection of the shafts 5 and 5^a with each other. This adjustment may be effected by 35 any suitable means. In practice, I preferably employ a take up means α^2 similar in construction to the one employed in the elevator and which construction is hereinafter set forth.

40 45 The elevator B comprises two frames which are rigidly secured together. One of these frames supports and guides the apron and is herein termed the apron-frame. The other supports the apron-frame and is arranged thereunder and is termed the base-frame. This base-frame extends under the whole or approximately the whole length of the apron-frame and engages the opposite ends of the latter. It is carried upon 50 wheels arranged under its ends, the wheels under one end being connected to what is referred to herein as a carrier, to which the draft is applied through the handle 100 when the elevator is being moved from place 55 to place. This carrier is mounted to turn relatively to the base-frame and suitable elements are employed to facilitate this turning movement. The several parts referred to are of special and very advantageous 60 construction in the herein-exemplified form of the invention, and will now be set forth in detail. The apron-frame has approximately horizontal upper and lower ends b and b', and an inclined section b^a intermediate of those ends and gradually merg-

ing into the same. The lower end b is in the plane of the contiguous section A', and the upper end may be in the plane of another conveyer indicated at D which may be an apron conveyer or like that already described, or a power or gravity conveyer of any suitable construction. The transfer of the packages from said conveyers to the elevator, or from the elevator to said conveyers, is thus accomplished without shock 70 either to the package or to the mechanism. The gradual emergence of the inclined section of the conveyer into the horizontal portions thereof, eliminating as it does abrupt angles at the junctions of these parts, causes 75 the packages to move readily and easily and without shock, across or along the junction points, and thereby materially improves the operation of the parts.

80 85 The apron frame is composed of a pair of suitably connected longitudinal members 25 and 26 at each side thereof. These members are formed of angle irons, whereby they are light and strong and at the same time form ways or tracks for the endless chains 90 27 which, together with transversely-arranged slats 28, constitute the apron of this conveyer.

90 95 The chains travel over sprockets 29 at the base and head of the elevator and suitable elements, as 30, are arranged at the junction of horizontal and inclined portions of the frame, to hold the chains down into the plane of the upper frame elements 25 at these places. Similar guiding means as 30^a 100 may be provided for the returning or lower runs of the chains. At intervals along the length of this apron means, such as strips 31 projecting above the plane of the surface thereof, are provided to prevent movement of the packages upon the apron.

105 110 The base-frame has two lower side members, 32, preferably formed of angle irons in order that they may be both light and strong. These members extend from the lower end of the elevator, in horizontal alignment, or approximately so, with the lower members 26 of the apron-frame, to a place which is approximately in vertical alignment with the upper end of the elevator. They preferably overlap the apron-frame members 26 at their forward ends.

115 120 Frame members are employed to connect the apron-frame with said members 32. Those here shown, comprise vertical members 33, having their upper ends secured to the apron frame members 25 and 26 at the upper end of the elevator; other vertical members 34 extending from the members 33 and fastened to the side members 25 and 26 intermediate the length of the apron-frame; horizontal members 35 secured to the vertical members 33 about midway the length of the latter and extending to the apron-frame members 25 and 26 to which they are 125 130

rigidly secured, diagonal truss rods or members 36, secured at their ends to the longitudinal members 32, at places adjacent to the lower ends of the vertical members 34, 5 and also secured to the apron-frame members; other diagonal truss rods or members, 37, the lower ends of which are arranged and secured contiguous to the junctions of members 33 and 35 and the upper ends of 10 which are secured to said apron-frame members between said members 35 and the upper ends of the elevator; and still other diagonal members 38, the lower ends of which are secured at or adjacent to the junction of the 15 members 32 and 33 and the upper ends of which are secured to the apron-frame members 25 and 26, at places between the members 34 and 35. All of these members are preferably made of angle iron.

20 Straps, as 39, are preferably arranged at intervals along the length of the apron-frame and connect with each other the members 25 and 26, at each side of said frame. These straps are preferably connected with 25 each other transversely of the apron frame, by tie-rods 39^a. The vertical members 33 are connected with each other by bracing members, herein shown as composed of horizontal and diagonal elements 40 and 41, re- 30 spectively.

One end of the supporting frame includes what may be generically referred to as a platform, to which the wheeled carrier hereinbefore referred to is connected. In the 35 exemplified form herein shown this is arranged under the elevated end of the elevator and at the junction of the members 32, 33 and 38. It is formed to provide an annular channel 42, the side wall of which furnishes 40 bearings for a series of shafts 43 upon which are mounted wheels 44 by which this end of the frame is supported by the wheeled carrier. This wheeled carrier comprises a frame 45, having pendent bearings 46 for 45 the shaft 47 of the carrying wheels 48 and a ring 49 which is arranged in juxtaposition to the inner wall (51) of the channel 42 and serves as a guide in the pivotal movement of the carrier. The wheels 44 make this move- 50 ment an easily-accomplished one. In the exemplified form, they are carried by the base frame and run upon the carrier, the latter preferably being provided with a wear plate 50, here shown as integral with 55 the ring 49.

The channel 42 is here shown as formed by an annular angle ring 52 and a separate ring 51 relatively disposed to close three sides of the channel, the fourth side being 60 formed by the wear plate 50.

In the exemplified form of the invention, both the platform and carrier are thus of open annular form.

From the foregoing description it will be clear that the rear end of the elevator is

movably mounted to swing upon an arc while leaving its lower or receiving end disposed in operative relation to the conveyer sections by virtue of which it is possible to move the discharge end of the elevator as 70 the operation of piling the packages goes on so that these packages may be piled to the best advantage. The upper end of the elevator may, if desired, be disposed in operative relation to a conveyer section D by 75 which packages may be conducted from the upper end of the elevator.

The several frame-members and the platform are secured together preferably as 80 follows:

The lower ends of the members 33 are cut away for the reception of the contiguous ends of the members 32, and the lower ends of the members 38 abut against the side walls of the members 33. At the junction 85 of these parts plates 55 are arranged and serve to secure together the several members referred to, being riveted thereto as shown. These plates may also be riveted, or otherwise suitably secured to the platform, and 90 this is true also of the members 32, whereby a rigid connection is made between the platform and the frame. The platform also supports a frame composed of legs 56 which diverge thereto from a place immediately 95 under the tie-members 40 of the uprights 33, to which tie members they are suitably secured. The lower ends of these legs are secured to the platform by brackets or plates 57 riveted or otherwise suitably secured to 100 the parts referred to; and cross pieces 58 are provided which brace the platform.

As already stated, the other end also of the elevator is mounted upon wheels (59) connected thereto in any suitable manner as 105 by means of a frame having a member 60 which extends across the lower end of the frame, underneath the same, and vertical members 61 which rise from the member 60 and are secured to the apron-frame members 25 and 26 at each side of the elevator. Suitable provision is made at this end of the elevator for taking up slack in the chains. The means shown for this purpose comprise bearings 62 for the shaft 63 of the sprockets, 115 said bearings being slidably mounted in supports 64, with suitable provision between the same for guiding the bearings in their adjustments. The bearings are adjusted by hand wheels 65, or other suitable means, 120 mounted on rods 65^a threaded in the supports.

The uprights 33 support a slide 66, through intermediate means which enable the outer end of the slide to be raised or lowered and to be moved laterally, in order to direct the packages to different predetermined parts of the pile, within the range of its adjustments. The intermediate means referred to are herein shown as composed of 125 130

brackets 67 secured to the frame members 33 and providing bearings for a shaft 68 upon which is mounted a frame 69 having lugs or ears 70 which engage the shaft 68, 5 and a pivotal connection, as the vertical pivot bolt 71, between the frame 69 and the rear end of the slide 66. A plate 72, which has depending ears or lugs 73 at its ends, is also mounted upon the shaft 68, under the 10 center of the frame 69, thus bracing the rear end of the slide at this place, where the greatest strain is imposed. Some suitable means, as clamping nuts 74 upon the ends of the shaft 68 will be provided to hold the 15 frame 69 and slide in the position to which they are adjusted upon the shaft 68, as the axis of such adjustment. The nut 75 upon the pivot bolt 71 similarly secures the slide in its horizontal adjustment upon the 20 frame 69.

For driving the apron, an electric motor as 76 mounted upon a base 77 carried by the members 32 is preferably employed. This motor is suitably connected with the 25 apron, as by means of a belt 78 extending over a pulley 79 mounted on a countershaft 80 carrying a pinion 81 which meshes into a gear 82 mounted on the shaft 83 of the upper sprockets of the apron. This constitutes 30 a form of reducing gearing preferably employed. The members 38 carry a shield 84 mounted over the motor 76 and protecting the latter against drippings from the packages. The motor is preferably connected 35 with a controller, not necessary to show herein, adapted to cause it to run the chain either forward or backward, thus adapting the elevator to lower as well as to raise packages.

While the embodiment shown and described is well adapted to serve the purposes sought, it is to be understood that this particular embodiment is merely exemplary and that the invention may be otherwise and variously embodied without departing from its 45 spirit or the scope of the subjoined claims.

Having thus described my invention, what I believe to be new, and desire to secure by Letters Patent and what I, therefore, claim is:—

1. A conveying apparatus comprising in 50 combination, a plurality of conveyer sections co-operatively associated with each other end to end and each having an endless traveling package supporting apron, the apron of the several sections lying close to each other end to end, and means to impart traveling movement to the aprons operable at varying angles of the sections, and an elevator to which said conveyer sections deliver, 55 comprising an endless traveling package supporting bed having an inclined portion and a substantially horizontal receiving end portion which lies substantially in the plane of the conveyer sections, the discharge end 60 of the elevator being mounted for arcuate 65

lateral movement while its receiving end remains in position to receive packages from said conveyer sections.

2. A conveying apparatus comprising in combination, a plurality of conveyer sections 70 co-operatively associated with each other end to end and having an endless traveling package supporting apron, the aprons of the several sections lying close to each other end to end, and means to impart traveling movement to the aprons operable at varying angles of the sections, and an elevator to which 75 said conveyer sections deliver, comprising an endless traveling package supporting bed having an inclined portion and a substantially horizontal receiving end portion which lies substantially in the plane of the conveyer sections, the discharge end of said elevator being mounted for arcuate lateral movement while its receiving end remains 80 in position to receive packages from said conveyer sections, a delivery slide carried by the discharge end of the elevator and adjustable to deliver the sacks or bags at varying heights, and means for mounting said 85 slide for arcuate movement with relation to the elevator.

3. A conveying apparatus comprising a plurality of portable sections having longitudinal driving shafts, a universal connection between confronting ends of said 95 shafts, through which one shaft derives motion from the next, endless traveling aprons forming the beds of the respective sections, and a driving connection between one end 100 of each apron and the driving shaft associated therewith, the other ends of the aprons being adjustable with relation to the driving shafts to take up slack without effecting the connection of the aprons with 105 said shafts or of the shafts with each other.

4. The combination with a frame, of transverse shafts at the ends thereof, a gear fixed on one of said shafts, sprocket wheels mounted on the shaft, endless chains engaging the sprockets, slats connecting the chains, and a longitudinal drive shaft having a gear at one end engaging the gear aforesaid, and a member of a universal connection at the opposite end of the longitudinal 110 shaft.

5. The combination with a pair of endless conveyers arranged end to end, of a longitudinally extending drive shaft for each conveyer, the longitudinal shaft of one of 115 the conveyers having a gear at one end for transmitting power to drive its own conveyer, and a connection at its opposite end for transmitting motion to the longitudinal shaft of the companion conveyer.

6. The combination of a pair of endless conveyers, arranged end to end, each conveyer including a frame, a transverse shaft at each end of the frame, a pair of sprockets carried by each shaft, a pair of endless 120

chains traveling over the sprockets, transversely disposed slats connecting the pair of chains, a gear wheel at one end of one of the transverse shafts, a drive shaft extending longitudinally of each of the conveyer frames, a gear at one end of one of the longitudinal drive shafts meshing with the gear of the transverse shaft aforesaid, and a coupling member at the opposite end of such longitudinal shaft adapted to be pivotally connected with a similar coupling at the adjacent end of the longitudinal shaft of the companion conveyer.

7. A conveying apparatus comprising in combination a plurality of conveyer sections co-operatively associated with each other end to end and each having an endless traveling package supporting apron, the aprons of the several sections lying close to each other end to end and means to impart traveling movement to the apron operable at varying angles of the sections and a conveyer to which said conveyer sections deliver, including a frame, and an endless traveling bed supported thereon, said conveyer having an approximately horizontal lower end portion, an approximately horizontal upper end portion, and an inclined portion arranged between and gradually merging into the upper and lower end portions, a substantially right angular supporting frame located beneath the conveyer and connected with the upper and lower horizontal portions of such conveyer, a turn table upon which the meeting sections of the right angular frame rest, and traction devices for the turn tables.

8. The combination with approximately horizontal upper and lower conveyers, of an elevator disposed therebetween and comprising approximately horizontal upper and lower end portions and an intermediate inclined portion which merges into said end portions, means for mounting that end of the elevator that is disposed toward the upper conveyer for bodily swinging movement into and out of substantially horizontal and

vertical alignment with the upper conveyer while leaving its receiving end in operative relation to the lower conveyer and a delivery slide carried by the elevator to receive the packages discharged from the elevator when the latter is moved out of alignment with the upper conveyer section.

9. In a conveyer, an inclined frame having an endless traveling package conveying means extending to the upper end thereof, uprights arranged under the upper end of the frame and supporting the frame, a transverse member carried by the uprights, a slide pivotally mounted on the transverse member, a rolling mounting for the frame disposed beneath the uprights and upper and lower conveyer sections with which the upper and lower ends of the endless traveling package conveying means are adapted to align.

10. In a conveyer, an inclined frame having an endless traveling package conveying means mounted thereon and comprising substantially horizontal upper and lower end portions and an intermediate inclined portion, upper and lower conveyer sections, the lower end of the traveling package conveying means lying substantially in the horizontal plane of the lower conveyer section and the upper end of the traveling package conveying means lying substantially in the horizontal plane of the upper conveyer section, uprights arranged under the upper end of the frame and supporting the same, a slide supported from said uprights and means for mounting the end of the frame that lies toward the upper conveyer section for arcuate swinging movement while leaving its lower end in operative relation to the lower conveyer section.

In testimony whereof I affix my signature in the presence of two witnesses.

MORRIS U. BERNHEIM.
